UNITED STATES PATENT OFFICE.

WILLIAM H. FORKER, OF MEADVILLE, PENNSYLVANIA, ASSIGNOR OF
ONE-HALF TO F. P. HOTCHKISS, OF MEADVILLE, PENNSYLVANIA.

HEADLIGHT.

No. 834,668.

Specification of Letters Patent.

Patented Oct. 30, 1906.

Application filed July 3, 1906. Serial No. 324,676.

To all whom it may concern:

Be it known that I, WILLIAM H. FORKER, a citizen of the United States of America, residing at Meadville, in the county of Crawford and State of Pennsylvania, have invented certain new and useful Improvements in Headlights, of which the following is a specification, reference being had therein to the accompanying drawings.

10 This invention relates to headlights particularly designed for automobiles, rural street-cars, and various types of vehicles.

15 The invention has for its object the provision of novel means for turning a headlight in any desired direction, whereby a roadside or object not in the path of travel can be observed.

20 Another object of this invention is to provide a revoluble headlight which can be easily and quickly manipulated by foot-power, the headlight being normally held stationary, but readily moved at any time and automatically returned to its original position.

25 With these and other objects in view, which will more readily appear as the invention is better understood, the same consists in the novel construction, combination, and arrangement of parts to be presently described, and specifically pointed out in the claims.

30 Referring to the drawings forming a part of this specification, like numerals of reference designate corresponding parts throughout the several views, in which—

35 Figure 1 is a side elevation of my improved headlight. Fig. 2 is a rear elevation thereof. Fig. 3 is a vertical sectional view of the same, and Fig. 4 is a cross-sectional view of the headlight-standard.

40 In the accompanying drawings I have illustrated a suitable support 1 for my improved headlight. This support may represent a dashboard of a vehicle or any suitable support. Upon the one side of the support 1 is secured, as at 2, a cylindrical casing 3, the top 4 of said casing partially resting upon the upper edge of the support, as at 5, and having a central opening 6.

45 Mounted upon the top 4 of the casing 3 is a grooved wheel 7, and passing through said wheel and the opening 6 of the casing is a tubular standard 8, said standard protruding into the casing, as shown in Fig. 3. The standard is flanged, as at 9, and is keyed to

55 the grooved wheel 7 by a pin 10, carried by said wheel and entering a notch 11, formed in the flange 9 of said wheel. To retain the grooved wheel 7 and the standard 8 upon the casing 3, I provide said standard with a detachable collar 12, which is secured to the 60 standard by a screw 14 directly beneath the top 4 of the casing, whereby the standard will be firmly held in a vertically-disposed position.

65 Suitably secured to the periphery of the grooved wheel 7, as at 15, is a chain or cable 16, which lies in the groove of said wheel and has its end fastened to L-shaped levers 17 and 18, pivotally mounted upon a plate 19, secured upon the inner side of the support 1. 70 The curved portions 20 of said levers are provided with tread-plates 21, whereby motor-men or operators of vehicles can manipulate the headlight without necessitating the use of their hands. The levers normally coincide and are retained in this position by a depending inverted-T-shaped spring 22, secured to the plate 19, the lower end of said spring engaging said lever and retaining the chain 16 taut upon the grooved wheel 7. 80

75 The standard 8 is provided with a reflector 23, containing a suitable lamp, (not shown,) which may be electrically illuminated by wires passing upwardly through the tubular standard 8 or by kerosene or a similar illuminating-oil. 85

From the foregoing it is obvious that when one of the tread-plates 21 is trod upon the associate lever will be moved in an opposite direction, placing the spring 22 under tension, which when released will return the headlight to its normal position. 90

95 The mechanism which I employ for shifting the headlight can be readily used in connection with searchlights and such illuminating devices as carried by vehicles or boats. I do not care to confine myself to the specific arrangement of parts as shown, since the lever 18 can be located a convenient distance from the headlight. 100

Such other changes as are permissible by the appended claims may be resorted to without departing from the spirit and scope of the invention.

What I claim, and desire to secure by Letters Patent, is—

1. The combination with a suitable support, of a casing attached thereto, a wheel

mounted on said casing, a standard journaled in the casing and on which the wheel is fixed, a lamp carried by said standard, a bracket secured to the support, a pair of L-shaped levers pivoted in said bracket, a chain passing over said wheel and having its ends connected to the upper ends of said levers, and a spring secured to the bracket and acting against said levers to normally hold the upper ends of the levers in the same plane, substantially as described.

2. The combination with a support, of a casing attached to said support, a standard journaled in the casing and provided with a headlight, a wheel fixed to the standard and

resting on the casing, a bracket secured to the support, a pair of L-shaped levers pivoted in said bracket, the lower arms of which serve as treadles, a chain passing over said wheel and having its ends connected to the upper ends of said levers, and means acting against the levers to normally hold the chain taut, and the levers in the same plane, substantially as described.

In testimony whereof I affix my signature in the presence of two witnesses.

WILLIAM H. FORKER.
